UNITED STATES PATENT OFFICE.

HARRY P. FROUD, OF NEW YORK, N. Y.

BUTTON.

SPECIFICATION forming part of Letters Patent No. 781,646, dated February 7, 1905.

Application filed April 13, 1904. Serial No. 203,019.

To all whom it may concern:

Be it known that I, HARRY P. FROUD, a citizen of the United States of America, residing at New York city, in the county of Kings and State of New York, have invented certain new and useful Improvements in Buttons, of which the following is a specification.

My invention has reference to improvements in buttons and analogous devices, and particularly to covered buttons.

The ordinary covered button heretofore made has the exterior annular surface of its metallic collet exposed, and as the metal is liable to corrosion the exposed portion of the collet is japanned. For better grade of buttons, particularly for those intended for better grade of clothing, this japanned surface is objectionable. It has been proposed to cover the entire back of the button with silk cloth, using said cloth also as a bunch or tuft for attaching the button to the fabric, but this construction is not adequate, as the covering does not give sufficient hold for the attaching-thread.

The object of my invention is therefore to provide a covered button having its back covered with a suitable cloth presenting a finished appearance corresponding to that of the front of the button, while a separate and independent tuft is provided for attaching purposes, thus producing a button covered in its entirety and at the same time affording means for its attachment to the cloth, the same as that of the ordinary cloth button.

To this end my invention consists, essentially, in a button comprising a cloth-covered shell, a perforated collet having an exterior cloth covering, and a tuft-piece within said collet and having a tuft projecting through the collet.

The nature of my invention will best be understood when described in connection with the accompanying drawings, in which —

Figure 1 represents a rear view of a button embodying my invention. Fig. 2 is a transverse section on the line 2-2, Fig. 1. Fig. 3 is a similar section through the shell and cloth. Fig. 4 is a similar section through the collet, tuft-piece, and collet-covering. Fig.

5 is a rear view of the collet and its covering-cloth.

Similar letters and numerals of reference designate corresponding parts throughout the several views of the drawings.

Referring now to the drawings, the letter *a*, Figs. 1, 2, and 3, designates the metallic shell of the button, which said shell, as usual in cloth buttons, is provided with an inturned edge or flange *b* and is covered with the cloth *c*, which latter also overlaps the edge or flange *b*. *d*, Figs. 2, 4, and 5, is the collet, which is perforated, as usual, at 4 for the passage of the tuft 1, forming part of the tuft-piece *e*, and is provided with a circumferential upturned flange 3. The cloth *f* also overlaps the inner periphery of the collet *d* and the flange 3. A usual tuft-piece *e* is employed, as before stated, which is preferably overlapped by the cloth covering *f* at the outer periphery of the collet *d*. 2 is a usual paper filling placed between the collet *d* and the shell *a*—that is to say, between the tuft-piece *e* and the shell, as usual.

The several parts of the button are assembled in the usual manner, the collet, shell, and paper filling wedging the several cloths and the tuft-piece when the button is closed.

It will be readily understood from the foregoing that the finished button presents a covered collet and a separate and distinct tuft, which latter is used for attaching the button to the fabric. In this respect it is distinguished from all such buttons in which the collet was covered and the covering used as attaching means for the button.

The configuration or shape of the button, the materials used in its manufacture, and the manner of assembling such parts may be varied without departing from the spirit of my invention, the essential feature of which is a perforated fabric-covered collet combined with an attaching-tuft passing through the collet.

What I claim as new is —

1. A cloth button comprising a covered shell, a perforated collet, a tuft-piece having a tuft extending through the perforation in the collet, and a separate, perforated covering-cloth for the collet extending over the exterior portion of the collet and over the two

edges of the same for securing said covering-cloth when the button is closed.

2. A button comprising a covered shell, a perforated collet, a tuft-piece having a tuft extending through the perforation in the collet, and a separate, perforated covering-cloth extending over the exterior portion of the collet.

In testimony whereof I have hereunto set my hand in the presence of two subscribing witnesses.

HARRY P. FROUD
